(57) **CLAIM**

The ornamental design for a sensor device, as shown and described.

DESCRIPTION

FIG. 1 is a top, front, right-side perspective view of a first embodiment of a sensor device;

FIG. 2 is a bottom, front, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof;

FIG. 9 is a top, front, right-side perspective view of a second embodiment of a sensor device;

FIG. 10 is a bottom, front, left-side perspective view thereof;

FIG. 11 is a front view thereof;

FIG. 12 is a back view thereof;

FIG. 13 is a left-side view thereof;

FIG. 14 is a right-side view thereof;

FIG. 15 is a top view thereof;

FIG. 16 is a bottom view thereof;

FIG. 17 is a top, front, right-side perspective view of a third embodiment of a sensor device;

FIG. 18 is a bottom, front, left-side perspective view thereof;

FIG. 19 is a front view thereof;

FIG. 20 is a back view thereof;

FIG. 21 is a left-side view thereof;

FIG. 22 is a right-side view thereof;

FIG. 23 is a top view thereof; and,

FIG. 24 is a bottom view thereof.

The dashed broken lines depict portions of the sensor device that form no part of the claimed design. The dot-dashed broken lines represent boundaries of the claimed sensor device and form no part of the claimed design.
